HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed October 10, 1929. Serial No. 398,660.

This invention relates to railway traffic controlling apparatus. One of the features of the invention comprises provisions for supplying train control energy to the rails adjacent both ends of a section of railway track by a single coding device. The invention also includes means for bringing the coding device into action in response to the entry of a train into the track section and for causing said device to apply energy to each end of the section in accordance with traffic conditions beyond said end. Another feature of the invention resides in provisions whereby the coding device may control the impedance of a track relay circuit so as to prevent energization of the track relay when energy is supplied to the adjacent end of the section and so that the track relay may on the other hand be energized in response to the application of energy to the opposite end of the section, following the vacating of said section by a train. Other features of the invention will be hereinafter described and claimed.

In the accompanying drawings Fig. 1 is a diagrammatic view illustrative of my invention and Fig. 2 is a diagrammatic view of a modification.

Similar reference characters refer to similar parts in both views.

Referring to the drawings, the numeral 5 designates a section of railway track to one end of which is connected a track relay 6 and to the other end of which section the secondary of a transformer 7 is connected. One terminal of the primary of the track transformer 7 is shown connected through wire 9, armature 10 and front contact 11 of track relay 6, and wire 12 to one terminal of the secondary of the line transformer 8. The other terminal of the secondary of said line transformer is connected through wires 13 and 14 to the second terminal of the primary of the track transformer 7. The latter is thus normally fed by said line transformer. The local element 6' of the track relay is permanently energized from line transformer 8, through wires 15, 16 connected to the wires 12, 13, respectively, as shown; while the track element 6'' of said relay is permanently con-

nected to the rails at the right hand end of the track section in series with the primary winding 17' of impedance transformer 17. When the track section is unoccupied, the secondary winding 17'' of impedance transformer 17 is short circuited through wires 18 and 19, front contact 20 and armature 21 of track relay 6, and wires 22 and 23.

When a train enters the track section it shunts the track element 6'' of the relay 6, thus de-energizing the same. Such de-energization of the track relay results in the disengagement of armature 21 from front contact 20, with consequent opening of the shunt circuit for the secondary 17'' of the impedance transformer 17. Also, the aforesaid de-energization of the track relay results in the disengagement of armature 10 from front contact 11 and the engagement of said armature with back contact 24. The latter is connected by a wire 25 with an armature 26 of a relay 27, which relay is responsive to traffic conditions to the left of section 5; said relay 27 being energized when said traffic conditions are safe and de-energized when said conditions are unsafe. Relay 27 may be controlled in accordance with the direction of travel as well as the location of trains, etc., to the left of section 5, and these features are all included in the term "traffic conditions." Since connections for rendering relay 27 responsive to traffic conditions as above set forth are well known in the art, they need not be here disclosed.

The reference character 31 designates a motor coder comprising a motor 31' connected with the secondary of transformer 8 over armature 35 and back contact 34 of relay 6 as will be apparent from the drawings. Motor 31', when energized, drives a movable contact element 49 at a constant frequency in such manner that contact 49 engages alternately with two fixed contacts 52 and 53. The motor coder 31 also comprises another movable contact element 48 which when motor 31' is operated is moved alternately into engagement with two fixed contacts 50 and 51 at a different frequency from the frequency of operation of contact 49. Operatively connected with contact element 48 and

moving in synchronism therewith is a contact element 30 arranged to engage a fixed contact 36 each time contact 48—50 is closed.

When relay 27 is energized, its armature 26 engages front contact 28 which is connected by wire 29 with contact element 30 of motor coder 31. The contact 36 of the motor coder is connected by a wire 37 with a back contact 38 of relay 6, which contact 38 is engaged, when relay 6 is de-energized, by armature 39 connected with wire 12.

It will thus be seen that when the track relay 6 is de-energized as aforesaid, while the relay 27 is energized, the primary of the track transformer 7 is connected to contact element 30 of the motor coder, so that each time that said contact element 30 engages contact 36, current from the line transformer 8 flows through the primary of said track transformer; the circuit being from one terminal of the secondary of line transformer 8, through wires 13 and 14, the primary of track transformer 7, wire 9, armature 10 and back contact 24 of relay 6, wire 25, armature 26 and front contact 28 of relay 27, wire 29, contact element 30 and contact 36 of motor coder 31, wire 37, back contact 38 and armature 39 of relay 6, and wire 12 to the other terminal of the secondary of the line transformer. It will thus be evident that when the track relay is de-energized, with relay 27 in energized condition, current impulses of a frequency corresponding to the number of engagements per unit time of contact element 30 with contact 36 will be supplied to the track transformer 7. If relay 27 is de-energized at the time the track relay is de-energized, current is supplied continuously from line transformer 8 to track transformer 7 through a circuit passing from transformer 8 through wires 13 and 14, the secondary of track transformer 7, wire 9, armature 10 and back contact 24 of relay 6, wire 25, armature 26 and back contact 40 of relay 27, wire 41, and wire 12 back to transformer 8. Thus upon de-energization of the track relay by the entry of a train into the track section 5, there is supplied to the transformer 7, and hence to the rails of said section, energy in the form of current impulses corresponding to the operation of contact element 30 of the motor coder or in the form of a continuous uninterrupted flow of current, depending upon whether the relay 27 is energized or de-energized, which in turn depends upon traffic conditions to the left of said track section 5. In other words, upon de-energization of track relay 6 energy in a form corresponding to traffic conditions to the left of the track section 5 is supplied by the track transformer 7 to the rails at the left hand end of said section.

A code feeding transformer 42 is adapted to feed coded energy to the rails at the right hand end of track section 5 in response to the

entry of a train into said section. One terminal each of the primary 42' of transformer 42 and the secondary 17" of impedance transformer 17 are shown connected together by the wire 23, which wire is also connected to armature 44 of a relay 45. The other terminal of said primary 42' of transformer 42 is connected through wires 43 and 13 to the secondary of line transformer 8. The relay 45 is responsive to traffic conditions to the right of section 5; being energized when said conditions are safe and de-energized when they are unsafe. The armature 44 is adapted to engage either a front contact 46 or a back contact 47 of relay 45; which contacts 46 and 47 are connected respectively to contact elements 48 and 49 operated by the motor coder. The contacts 50 and 52 of the motor coder are connected to the previously mentioned wire 19 connected to the secondary of transformer 17; while the contacts 51 and 53 are connected to wire 37 previously described as connected to back contact 38 of track relay 6.

It will now be seen if relay 45 is energized when the track relay 6 is de-energized upon entry of a train into the track section 5, current from the line transformer 8 is supplied to the code feeding transformer 42 each time that contact element 48 of the motor coder engages contact 51; the circuit for said current being from one terminal of the secondary of line transformer 8 through wires 13 and 43, the primary of transformer 42, wire 23, armature 44 and front contact 46 of relay 45, contact element 48 and contact 51 of the motor coder, wire 37, back contact 38 and armature 39 of track relay 6, and wire 12 to the other terminal of the secondary of line transformer 8. Current impulses of a frequency corresponding to the number of engagements per unit time of element 48 and contact 51 are thus supplied to transformer 42 and thence to the rails at the right hand end of track section 5, said impulses indicating that traffic conditions to the right of said section are safe. It will be noted that at the time contact element 48 engages contact 51 it is disengaged from contact 50 and the secondary 17" of impedance transformer 17 is open circuited; whereby the impedance of the winding 17' of said transformer, which is in series with winding 6" of the track relay 6, is increased sufficiently to prevent any substantial energization of said winding 6" by the aforesaid current impulses supplied by transformer 42.

When track relay 6 and relay 45 are de-energized, current impulses are supplied to transformer 42, and thence to the rails, by line transformer 8, by way of the armature 44, wire 47, and motor coder contacts 49 and 53; said impulses being of a frequency corresponding to the number of engagements per unit time of element 49 and contact 53

and being indicative of unsafe conditions to the right of section 5. Each time that contact element 49 engages contact 53 said element is out of engagement with contact 52, so that the secondary winding 17" of transformer 17 is open circuited and the impedance of the primary 17' of said transformer increased as above set forth to prevent any considerable amount of current from flowing 10 through winding 6" of the track relay.

In addition to the prevention of a substantial flow of current through coil 6" by virtue of the impedance of transformer coil 17' when coil 17" is open circuited; the secondary winding 42" of transformer 42 may as a further precaution be so connected to coil 6" that any current that does feed into the latter coil will be in a direction to open the track relay. However, the impedance of 20 transformer winding 17", when winding 17" is open-circuited, is sufficient to prevent energization of the track relay by the current supplied by the code-feeding transformer 42; so that said impedance suffices by itself to 25 prevent misoperation of the relay in response to the impulses supplied by said code-feeding transformer.

When coder contact 48 or 49 is engaged with its associated lower contact 50 or 52 the 30 secondary 17" of impedance transformer 17 is short circuited by way of wire 23, armature 44, contact 46 or 47, the corresponding contact element 48 or 49 and its respective lower contact 50 or 52, wire 19, and wire 18. It should 35 be noted that said secondary of transformer 17 is short circuited during the same portion of the code cycle during which the primary of track transformer 7 is energized. After the track section 5 is vacated, the track relay 40 6 will become energized during the next down stroke of motor coder contact 48 or 49, the secondary of impedance transformer 17 being at that time short circuited and the track element 6" of relay 6 receiving energy 45 through the rails from track transformer 7. Armatures 21, 10, 35 and 39 are thereupon shifted to their positions shown in Fig. 1, the motor coder is de-energized, and the relay 6 is thereafter maintained energized by the uninterrupted current supplied to the rails by 50 transformer 7.

The contact elements 30 and 48 of the motor coder are driven in synchronism and engage their back contacts 36 and 50 respectively 55 during the same interval; whereby current interrupted by contact element 30 is supplied by transformer 7 to the rails concurrently with the engagement of contact element 48 with contact 50. While the contact element 49 is operated at a different rate from contact members 30 and 48, the latter are driven considerably more rapidly than said element 49 (for example, said element 49 may engage each of its associated contacts 52, 53 alternately 60 65 80 times per minute as compared with

180 engagements of each of contacts 50, 51 alternately by contact element 48, which is operated in synchronism with element 30); and during each time that said element 49 engages its back contact 52, the member 30 will 70 engage its back contact 36 at least once. Thus, whether the secondary or impedance transformer 17 be short circuited by contact element 49, or by the contact element 48, the track relay 6 will be energized by the first 75 impulse applied to the rails by transformer 7 following the vacating of the track section 5. Of course, if at the time the track section is vacated, uninterrupted current is being supplied by transformer 7 to the rails through armature 26 and back contact 40 of relay 27, the track relay 6 will likewise be energized as soon as the secondary of impedance transformer is short circuited by either contact element 48 or contact element 49. 80 85

While I have shown the track transformer 7 as supplying either interrupted current or uninterrupted current to the rails in response to de-energization of the track relay and depending upon the condition of relay 27, it will 90 be evident that by connecting back contact 40 to a contact element driven by the motor coder at a different rate from element 30 (80 cycles per minute, for example) said transformer 7 may be caused to supply coded energy of a 95 corresponding frequency to the rails when the relay 27 is de-energized. Such an arrangement is indicated in Fig. 2, wherein wire 41 is shown connected to a contact element 55 operated by the motor coder in synchronism with contact element 49 so as to be engaged with and disengaged from contact 56 at the same time that said element 49 is engaged with and disengaged from back contact 52. Contact 56 is connected to wire 37, 100 so that each time said contact is engaged by element 55 an impulse of current is transmitted to track transformer 7. 105

It will be seen that I have provided means 110 for supplying train control energy alternately to the respective ends of a track section by a single coding device. The coded energy supplied to the rails by the transformers 7 and 42 respectively may be utilized in any suitable or convenient way as by the usual apparatus mounted on the front of the locomotive and responsive to current impulses applied to the rails of the track section at a point ahead of the train for causing indications corresponding to said impulses to be given in the locomotive cab. It will be evident that by applying coded energy through transformer 7 to the rails at the left hand end of the section in accordance with the traffic conditions to the left of said section, a train entering said section from the right and equipped with the conventional receiving apparatus aforesaid will receive indications of said traffic conditions; while conversely if such train enters said section from the left it 115 120 125 130

will receive from the impulses applied to the rails by transformer 42 indications of traffic conditions to the right of said section.

The terms and expressions which I have employed are used as terms of description and not of limitation, and I have no intention, in the use of such terms and expressions, of excluding any mechanical equivalents of the features shown and described or portions thereof, but recognize that various structural modifications are possible within the scope of the invention claimed.

What I claim is:

1. In combination, a section of railway track, means for applying uninterrupted current to the rails adjacent one end of said section, and means effective upon the entry of a train into the track section for applying coded train control energy to the rails adjacent both ends of the track section.

2. In combination, a section of railway track, means for applying uninterrupted current to the rails adjacent one end of said section, and means effective upon the entry of a train into the track section for applying coded train control energy to the rails adjacent both ends of the track section alternately.

3. In combination, a section of railway track, means responsive to entry of a train into said section, means controlled by the first mentioned means for applying impulses of train control energy to both ends of said section, and means responsive to traffic conditions adjacent each end of said section for controlling the frequency of the impulses applied by the second mentioned means to the corresponding end of the section.

4. In combination, a section of railway track, a track relay for said section, means controlled by said relay for applying impulses of train control energy alternately to the respective ends of a track section, and relays responsive to traffic conditions beyond each end of said section for controlling the frequency of the impulses applied by said means to the corresponding end of the section.

5. In combination, a section of railway track, a track relay de-energized upon entry of a train into said track section, means controlled by said relay for applying train control energy to the ends of said section, a transformer having a primary winding in circuit with said relay, and a circuit for the secondary of said transformer controlled by said energy applying means.

6. The method of controlling train movements in either of opposite directions over a section of railway track, said method consisting of applying coded train control energy to the rails adjacent both ends of the section and of controlling the characteristics of the current applied to each end of this

section in accordance with traffic conditions beyond such ends of the section.

7. In combination, a section of railway track, means for transmitting coded energy, and means effective upon the entry of a train into the track section for causing said first mentioned means to apply coded energy to the rails adjacent both ends of the track section.

8. In combination, a section of railway track, a coding device, and means responsive to the entry of a train into the track section for causing said coding device to supply coded energy to the rails adjacent the respective ends of said section.

9. In combination, a section of railway track, a coding device, and means responsive to the entry of a train into the track section for causing said coding device to supply coded energy to the rails adjacent the respective ends of said section alternately.

10. In combination, a section of railway track, a coding device, means for at times causing said coding device to supply coded energy to the rails adjacent the respective ends of said section, and means responsive to traffic conditions adjacent each end of said section for controlling the application of energy by said coding device to the corresponding end of the section.

11. In combination, a section of railway track, a coding device, means responsive to the entry of a train into the track section for causing said coding device to supply coded energy to the rails adjacent the respective ends of said section, and means responsive to traffic conditions adjacent each end of said section for controlling the application of energy by said coding device to the corresponding end of the section alternately.

12. In combination, a section of railway track, a coding device, means including a contact controlled by said coding device for supplying coded energy to the rails adjacent one end of said track section, means including another contact controlled by said coding device for supplying coded energy to the rails adjacent the other end of said track section, and means responsive to the entry of a train into said section for controlling said coding device.

13. In combination, a section of railway track, a coding device, means including a set of contacts controlled by said coding device for supplying coded impulses of different characteristics to the rails adjacent one end of said track section, means including another set of contacts controlled by said coding device for supplying coded impulses of different characteristics to the rails adjacent the other end of said track section, and means responsive to traffic conditions adjacent each end of the track section for determining the characteristics of the impulses applied by said

coding device to the corresponding end of said section.

14. In combination, a section of railway track, track relay, means for connecting said relay across the rail adjacent one end of the section, a coding device controlled by said relay for applying coded train control energy to the rails adjacent the ends of said section, and means controlled by said coding device for increasing the impedance of the track relay circuit concurrently with the application of coded energy to the end of the section adjacent said track relay.

15. In combination, a section of railway track, a track relay, means for connecting said relay with the rails adjacent one end of said section, a coding device controlled by said relay for applying coded train control energy to the rails adjacent the ends of said section alternately, and means controlled by said coding device for increasing the impedance of the track relay circuit concurrently with the application of coded energy to the end of the section adjacent said track relay.

25 16. In combination, a section of railway track, a track relay, means for connecting said relay with the rails adjacent one end of said section, a coding device controlled by said relay for applying coded train control energy to the rails adjacent the ends of said section, and means comprising contacts operated synchronously by said coding device for decreasing the impedance of track relay circuit concurrently with the application of energy to the end of the section opposite said track relay.

30 17. In combination, a section of railway track, a track relay, means for connecting said relay with the rails adjacent one end of said section, a coding device controlled by said relay for applying coded train control energy to the rails adjacent the ends of said section alternately, and means comprising contacts operated synchronously by said coding device for decreasing the impedance of the track relay circuit concurrently with the application of energy to the end of the section opposite said track relay.

35 18. In combination, a section of railway track, a coding device comprising two contact elements operating in synchronism, means controlled by one contact element for supplying coded energy to the rails adjacent one end of the section, and means controlled by the other contact element for supplying coded energy to the rails adjacent the other end of the section, whereby coded energy is supplied to the two ends of the section alternately.

40 19. In combination, a section of railway track, a transformer, a track relay connected across the rails adjacent one end of said section through one winding of said transformer, means for normally supplying uninterrupted current to the rails adjacent the other

end of the section, a coding device comprising a first contact and a second contact operating periodically in synchronism, a third contact arranged to be closed when said first and second contacts are open, means operating when said track relay is de-energized and effective at times to supply coded train control energy to said other end of the section over said first contact and to supply coded train control energy to said one end of the section over said third contact, a first circuit for the remaining winding of said transformer including a front contact of said track relay, and a second circuit for said remaining transformer winding including said second contact.

In testimony whereof, I have signed my name to this specification this 7th day of October, 1929.

HOWARD A. THOMPSON.
